(57) CLAIM

The ornamental design for a planter, as shown and described.

DESCRIPTION

FIG. 1 is a perspective view of a planter showing my new design;

FIG. 2 is a front view of the planter, a rear view being a mirror image;

FIG. 3 is a left side view of the planter, the right side view being a mirror image; and,

FIG. 4 is a top view of the planter.

A bottom view is of the design is flat and unornamented. Broken lines shown in the FIGS. are for illustrative purposes and form no part of the claimed design.
